UNITED STATES PATENT OFFICE.

JOHN E. BELL, OF NEW YORK, N. Y., ASSIGNOR TO THE BABCOCK & WILCOX COMPANY, OF NEW YORK, N. Y., A CORPORATION OF NEW JERSEY.

WATER-TUBE BOILER.

No. 857,017.

Specification of Letters Patent.

Patented June 18, 1907.

Application filed November 7, 1906. Serial No. 342,347.

To all whom it may concern:

Be it known that I, JOHN E. BELL, of New York, county and State of New York, have invented a new and useful Water-Tube Boiler, of which the following is a full, clear, and exact description, reference being had to the accompanying drawings, forming part of this specification, in which—

Figure 1 is a sectional side elevation showing one form of boiler constructed in accordance with my invention; and Fig. 2 is a front elevation of the same, one half in section.

My invention relates to the class of water tube boilers, wherein vertical or vertically-inclined tubes are arranged in banks connecting upper and lower drums, a source of heat being in front of the front bank, and the gases being directed in successive up and down passes among the tubes.

The object of the invention is to provide a simple, compact and efficient boiler of this type in which added heating surface is provided between the banks and so connected as to insure a circulation therethrough.

In the drawings, 2 and 3 represent upper transverse steam and water drums, and 4 and 5 corresponding mud drums which are connected with the upper drums by banks of tubes 6 and 7. I have shown five rows of tubes for each bank proper, with the ends of the tubes curved to enter the cylindrical drums. The number of rows in each bank may, however, be varied, though there are preferably at least four rows. The tubes of the banks proper may be made straight if desired, by providing suitable struck-up portions or tube seats in the drums. The lower drums are preferably connected by a row of tubes or nipples 8 and the steam spaces of the steam and water drums are connected by a row of steam circulators or pipes 9. The water spaces of the steam and water drums are preferably not directly connected with each other, though a row of direct water circulators may be used, if desired.

Between the banks proper, I arrange two rows of tubes 10 and 11 between which extends the vertical baffle 12 resting at its lower end on the pier 13 between the mud drums. The tubes of the row 10 are curved forward at their upper ends to enter the water space of the front upper drum 2 and are bent or curved rearwardly at their lower

ends to enter the rear mud drum, passing through suitable holes in the lower part of the baffle. The tubes of the row 11 are curved rearwardly at their upper ends to enter the upper drum and are also bent rearwardly at their lower ends to enter the rear mud drum. The row of tubes 10 is preferably close to the front bank, thus leaving a considerable space between the tubes 11 and the front row of tubes 7; and I preferably provide a rearwardly projecting shelf 14 on the baffle 11 which will tend to hold the gases among the tubes of the rear bank in their downward flow. If the tubes 10 are spaced farther apart from the front bank a shelf or shelves may be arranged to project forwardly from the baffle 11. A deflector 15 may also be at the inside of the front wall to hold the gases in the front bank of tubes; and this deflector or baffle brick may also be used at the inside of the rear baffle or wall 16 forming the front of the outlet flue 17. The outlet port may also be arranged at the lower end of the rear bank, if desired. The space between the tubes 7 and 11 is preferably sufficient to allow the entrance of a man through side ports 18, thus giving access for cleaning and repairs.

The furnace 19 may be of the ordinary external type, the gases rising among the tubes of the front bank, crossing the top of the baffle and descending among the tubes of the rear bank.

The steam is preferably taken off from the drum 3 only, thus aiding in preventing the discharge of wet steam. The feed, water preferably enters the rear upper drum 3, which is shown as being fed in through pipe 20. By connecting the pipes 10 and 11 to the rear mud drum while one set enters the front upper drum and the rear set enters the rear upper drum, I provide a circulation up the front bank of tubes 6 and down the tubes 10 and thence forward with the feed through nipples 8. There will also be circulation up the rear bank of tubes 7 and down through the tubes 11, which are in a relatively cooler location.

The advantages of my invention result from the peculiar connections of the added tubes between the main banks, which give a positive down circulation from the front upper drum, thereby relieving it and giving efficient circulation in the added tubes. The

structure is compact, and may be cheaply made, and the use of a third steam and water drum with its bank of tubes is done away with. The number of tubes or rows added between the banks may be varied, as well as their spacing relative to each other and the main banks. The number of tubes in each bank proper may be varied, although five rows are preferably used. Direct water connection may be provided between the upper drums and between the lower drums, the tubes of the main bank may be either strictly vertical, or inclined in a vertical direction, the mud drum may be in the form of a double-compartment drum instead of two separate drums, and many other changes may be made without departing from my invention.

I claim:—

1. In a water tube boiler, a plurality of upper transverse steam and water drums, a plurality of connected transverse mud drums, banks of tubes connecting the upper and lower drums, an added row of tubes between the banks, said tubes entering the front upper drum and the second mud drum, and a baffle in the rear of said added row of tubes and between it and the rear bank of tubes; substantially as described.
2. In a water tube boiler, a plurality of upper transverse steam and water drums, a plurality of transverse mud drums, banks of tubes connecting the upper and lower drums, and at least two added rows of tubes between

the main banks, both of said rows entering the rear mud drum, one row being connected to the front upper drum and the other row to the rear upper drum; substantially as described.

3. In a water tube boiler, a plurality of upper transverse steam and water drums, a plurality of transverse mud drums, banks of tubes connecting the upper and lower drums, at least two added rows of tubes between the main banks, both of said rows entering the rear mud drum, one row being connected to the front upper drum, the other row to the rear upper drum, and a baffle extending vertically between the two rows of added tubes; substantially as described.

4. In a water tube boiler, a plurality of upper transverse steam and water drums, a plurality of transverse connected mud drums, banks of tubes connecting the upper and lower drums, and at least two added rows of tubes between the main banks, both of said rows entering the rear mud drum, one row being connected to the front upper drum and the other row to the rear upper drum; substantially as described.

In testimony whereof, I have hereunto set my hand.

JOHN E. BELL.
